BOW TIE RACK

Clifford C. Swanson, 1715 27th St., Zion, Ill.

Filed Nov. 21, 1960, Ser. No. 62,916

Term of patent 14 years

(Cl. D33—8)

Fig. 3

Fig. 2

Fig. 1

FIG. 1 is a perspective view of a bow tie rack showing my new design;

FIG. 2 is a side elevational view thereof;

FIG. 3 is a front elevational view thereof;

FIG. 4 is a bottom plan view thereof; and

FIG. 5 is a fragmentary top plan view thereof.

In FIGURES 2 and 3 an outline of a bow tie is shown in dot dash lines for illustrative purposes only.

The back of the bow tie rack in the design shown is plain and unornamented.

I claim:

The ornamental design for a bow tie rack, substantially as shown and described.
